UNITED STATES PATENT OFFICE.

JAMES E. McKEON, OF WILKES-BARRE, PENNSYLVANIA.

CONCRETE-MIXER.

No. 901,024.

Specification of Letters Patent.

Patented Oct. 13, 1908.

Application filed June 12, 1908. Serial No. 438,191.

To all whom it may concern:

Be it known that I, JAMES E. McKEON, a citizen of the United States, residing at Wilkes-Barre, in the county of Luzerne and State of Pennsylvania, have invented a new and useful Concrete-Mixer, of which the following is a specification.

This invention relates to machines for mixing concrete and similar material and has for its object to provide a strong, durable machine of this character by means of which the several ingredients may be thoroughly mixed or blended.

A further object of the invention is to provide a machine including a casing having a shaft journalized therein and provided with spaced longitudinally disposed mixing blades, there being a series of agitating fingers surrounding the shaft to assist in mixing the material when the shaft is rotated.

A still further object of the invention is generally to improve this class of devices so as to increase their utility, durability, and efficiency.

Further objects and advantages will appear in the following description, it being understood that various changes in form, proportions and minor details of construction may be resorted to within the scope of the appended claims.

In the accompanying drawings forming a part of this specification: Figure 1 is a longitudinal sectional view of a mixing machine constructed in accordance with my invention. Fig. 2 is a transverse sectional view taken on the line 2--2 of Fig. 1. Fig. 3 is a perspective view of the mixing element detached.

Similar numerals of reference indicate corresponding parts in all of the figures of the drawings.

The improved mixing machine forming the subject matter of the present invention comprises a casing or housing 5 preferably cylindrical in shape, as shown, and mounted on a suitable supporting frame 6.

The side walls of the casing at the upper end thereof are flared laterally at 7 to produce a hopper 8 through which cement, sand and the like is introduced into the mixing chamber 9.

Journalized in the end walls of the casing 5 is a longitudinally disposed shaft 10 to which is rigidly secured in any suitable manner a plurality of spaced wheels or spiders 11.

Interposed between the spiders 11 and surrounding the shaft 10 are tubular members 12 preferably rectangular in cross section and provided with terminal arms 13 for attachment to the rim 14 of the spiders, as shown. The rims 14 are each provided with a plurality of spaced lugs 15 to which are bolted or otherwise rigidly secured at 16 longitudinally disposed mixing blades 17, which latter revolve within the chamber 9 when the shaft is rotated thereby to thoroughly mix the sand, cement and other material in said chamber.

The walls of the tubular member 12 are formed with a plurality of threaded openings 18 for engagement with the correspondingly threaded ends of suitable agitating pins or fingers 19, which latter serve to assist in mixing the ingredients and force the material outwardly in engagement with the mixing blades 17.

The bottom of the cylinder 5 is provided with a longitudinally disposed opening 20 for discharging the contents of the chamber 9 after the same has been thoroughly mixed, said opening being normally closed by a pair of cooperating doors 21 pivotally mounted at 22 on the bottom of the casing, as shown, and fastened in closed position by a catch or similar locking device 23.

One end of the shaft 10 is provided with a wheel or pulley 24, which latter may be connected through the medium of a belt with an engine or other source of power for rotating the mixing element. If desired, however, a hand crank may be secured to one end of the shaft 10 so that the machine may be operated manually.

In operation the sand, cement, gravel or other material is poured into the hopper 8 and the mixing element rotated. As the mixing element rotates the blades 17 will engage the material within the chamber 9 and elevate the same until the blades reach approximately a vertical position when the material will drop off the blades and on to the mixing fingers 19, the latter serving to draw the material thus deposited outwardly in engagement with the interior walls of the casing and against the mixing blades so that on the next revolution of the mixing element the material will be again carried upwardly and allowed to fall on said mixing fingers. After the several ingredients are thoroughly mixed or blended the locking device 23 is

released and the doors 21 moved to open position thus permitting the discharge of the contents of the mixing chamber.

It will of course be understood that the machines may be made in different sizes and shapes and that any desired number of mixing blades or agitating fingers may be employed.

Having thus described the invention what is claimed is:

1. A mixing machine including a casing, a shaft mounted for rotation within the casing, spiders secured to and mounted for rotation with the shaft, tubular members interposed between the spiders, longitudinally disposed mixing blades carried by the spiders, and agitating devices secured to the tubular members.
2. A mixing machine including a casing, a shaft journaled in said casing, spaced spiders rigidly secured to the shaft and provided with peripheral lugs, longitudinally disposed mixing members connecting the lugs, tubular members interposed between the spiders, agitating pins threaded in the tubular members, and means for rotating the shaft.
3. A mixing machine including a casing, a shaft journaled in the casing, spaced spiders secured to and mounted for rotation with the shaft, tubular members interposed between the spiders and provided with oppositely disposed arms for attachment to the adjacent spiders, longitudinally disposed mixing blades secured to the peripheral edges of the spiders, and intersecting agitating fingers carried by the tubular members.
4. A mixing machine including a casing, a shaft mounted for rotation within the casing, spaced spiders secured to and mounted for rotation with the shaft, lugs extending laterally from the peripheral edges of the spiders, longitudinally disposed mixing

blades secured to the lugs, tubular members interposed between the spiders and provided with angularly disposed arms for attachment to said spiders, there being threaded openings formed in the walls of the tubular members, and agitating pins engaging the threaded walls of the openings.

5. A mixing machine including a casing having a mixing chamber and provided with a hopper communicating with said chamber, a shaft mounted for rotation within the casing, spaced spiders secured to the shaft and mounted for rotation with the latter within the mixing chamber, tubular members surrounding the shaft and interposed between the spiders, a plurality of spaced lugs extending laterally from the peripheral edges of the spiders, longitudinally disposed mixing blades secured to said lugs, and intersecting agitating fingers carried by the tubular members.

6. A mixing machine including a casing having a mixing chamber and provided with a hopper communicating with said chamber, there being a discharge opening formed in the bottom of the casing, a shaft journaled in the casing, spaced spiders secured to and mounted for rotation with the shaft, tubular members surrounding the shaft and interposed between the spiders, mixing blades secured to the peripheral edges of the spiders and extending the entire length of the mixing chamber, intersecting agitating fingers carried by the tubular members, and a closure for the discharge opening in the casing.

In testimony that I claim the foregoing as my own, I have hereto affixed my signature in the presence of two witnesses.

JAMES E. McKEON.
